UNITED STATES PATENT OFFICE.

ELIZABETH DAY AND MAURICE GOLDBERGER, OF CHICAGO, ILLINOIS; SAID GOLDBERGER ASSIGNOR TO SAID DAY.

INDICATOR OR POINTING DEVICE.

Application filed July 14, 1928. Serial No. 292,842.

This invention relates to devices for indicating or pointing to the words in sentences, or successively to various characters or illustrations for directing the attention of the observer thereto and is adapted for various uses, such as by copyists, typesetters, speakers, advertising and the like, and one of the objects of the invention is to provide an improved device of this character which will be of a comparatively simple and compact construction and effective, efficient and automatic in action.

A further object is to provide improved means whereby the indicating or pointing element may be readily set to any desired position and at any time in the operation thereof without necessitating the stopping of the driving or actuating power mechanism thereof.

20 To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention, and in which

Figure 1 is a top plan view of a device of this character constructed in accordance with the principles of this invention.

Figure 2 is an enlarged horizontal sectional view as taken on line 2—2, Figure 3.

Figure 3 is a transverse vertical sectional view taken on line 3—3, Figure 2.

Figure 4 is a detail sectional view taken on line 4—4, Figure 1.

Figure 5 is a detail sectional view taken on line 5—5, Figure 4.

40 Figure 6 is a detail sectional view taken on line 6—6, Figure 4.

Figure 7 is a detail elevation of the releasing mechanism whereby the pointer or indicator may be set to any desired position.

45 Figure 8 is an enlarged detail sectional view of the lower end of the mechanism forming a continuation of Figure 2.

50 Referring more particularly to the drawings the numeral 10 designates generally a casing in which all of the mechanism is housed and which casing may be of any desired size and configuration and constructed of any suitable material.

55 Journaled in the casing and in suitable bearings is a threaded shaft 11 which has a

constant direction of rotation, and loosely mounted upon the shaft is a clutch member 12. A clutch member 13 is keyed to the shaft 11 and is adapted to be shifted into and out of engagement with the clutch member 12 for locking and unlocking the clutch member 12 with respect to the shaft.

Connected with the clutch member 12 and for rotation therewith is a gear 14 with which a gear 15 meshes. Connected with the gear 15 for rotation therewith is a gear 16, the latter being secured to a shaft 17 and which shaft is journaled in suitable bearings 18.

A pinion gear 19 is connected with the shaft 17 for rotation therewith and this pinion gear meshes with another gear 20 that is secured to a shaft 21, the gear 20 meshing with a gear 22 that is secured to a shaft 23 for rotation therewith. This shaft 23 is mounted in suitable bearings and has keyed to it an element 24 preferably of the friction drive type. The element 24 has frictional engagement with a drive disc 25 secured to a shaft 26 mounted in suitable bearings 27, and to the end of the shaft 26 by means of a suitable coupling device a power drive shaft 29 is secured and this shaft receives its motion from any suitable source of power.

A spring 30 is provided between the disc 25 and shoulder 31 which tends normally to hold the friction drive elements 25 and 24 in contact with each other.

The speed of rotation of the shaft 23 and consequently the shaft 11 is controlled by shifting the friction element 24 toward and away from the axis of rotation of the friction disc 25.

This is accomplished in any suitable manner, preferably by means of an arm or lever 32 which is connected to a shaft 33 that extends through the top of the casing, and to the shaft is connected a handle or button 34 arranged in a suitable position for the operator. An indicator or pointer 35 may be provided which co-operates with graduations 36 to indicate the rate of speed of the shaft.

Journaled in suitable bearings and preferably in alinement with the shaft 23 but separate therefrom, is another shaft 37 that has 105 connected with it an elongated toothed portion 38, for a purpose to be set forth. This shaft 37 and the portion 38 thereof is adapted for rotary movement in a forward and backward direction and to that end there is 110

provided a gear wheel 39 which is loosely mounted upon the shaft 37.

A clutch member 40 is connected with the gear 39 for rotation therewith and a double clutch member 41 is connected with the shaft 37 for rotation therewith and for slidable movement lengthwise thereof so that one portion of the clutch member 41 will engage the clutch member 40 to lock the gear 39 for rotation with the shaft 37 and another portion of the double clutch member 41 will engage a clutch member 42 which is connected with a gear 43, loosely mounted upon the shaft 37, to lock the latter gear for rotation with the shaft.

By alternately locking and unlocking the reciprocating gears 39 and 43 with respect to the shaft 37 the direction of rotation of the shaft 37 may be controlled and this is accomplished in the following manner. Meshing with the gear 39 is a pinion gear 44 which is secured to the shaft 21 of the gear 20 for rotation therewith so that when the clutch member 40 is locked to the shaft 37 and the shaft 23 is rotating, motion will be imparted from the shaft 23 through the intermeshing gears 22—20, shaft 21 and intermeshing gears 44—39 to the shaft 37 when the clutch member 41 is in the position shown in Figure 2.

When the clutch member 41 is shifted so as to release the clutch member 40 and lock the clutch member 42 and gear 43 with respect to the shaft 37, motion will be imparted to the shaft 37 from the shaft 23, intermeshing gears 22—20—19, shaft 17, gear 16 and gear 43 which is secured to the clutch member 42 for rotation therewith.

Thus it will be seen that by shifting the clutch member 41 the direction of rotation of the shaft 37 and portion 38 thereof will be controlled.

The clutch member 40 is adapted to be automatically controlled in any suitable manner so that when the shaft 38 has rotated for any desired extent in one direction the direction of rotation of the shaft 37 will be reversed.

To that end there is provided an arm or lever 45 pivotally mounted by one end as at 46 to a suitable support, the other end of the lever being connected with the clutch member 41.

Slidably in suitable bearings 47 is a bar or rod 48, one end of which is connected with a lever 49 pivoted intermediate its ends as at 50, the other end of the lever 49 being connected with the clutch member 13 which is shiftable longitudinally upon the shaft 11.

A suitable connection 51 is provided with the member 48 and the arm or lever 45 and a spring 52 anchored to a fixed support 53 and connected as at 54 with the arm or lever 49, is provided which tends normally to shift the member 48 in a direction to move the arm or lever 45 to position the clutch member 41 as shown in Figure 2.

After the shaft 37 has rotated to any desired extent, means are provided whereby the direction of rotation of the shaft 37 may be reversed and to that end there is provided a cam member 55 which is connected with a shaft 56 journaled in suitable bearings. The cam member 55 is preferably formed on a gear 57 which latter meshes with a gear 58 carried by a shaft 59 rotatably supported in suitable bearings 60 and connected with the member 48 is an anti-friction roller 61 which is so positioned that at a predetermined time in the cycle of operation of the device the cam member 55 will be rotated to such an extent that it will operate upon the anti-friction roller 61 to shift the member 48 against the stress of the spring 50 and thereby shift the arm or lever 45 to shift the clutch member 41 out of engagement with the clutch member 40 to release the gear 39 with respect to the shaft 37 and into operative or locking engagement with the clutch member 42 to secure the gear 43 to the shaft for rotation therewith, thereby through the medium of the respective train of gears as already described, changing the direction of rotation of the shaft 37.

When the clutch member 40 and the gear 39 are locked to the shaft 37 a comparatively slow speed of rotation will be given to the shaft 37 by reason of the different ratios of the gears 39 and 44, but when the shaft 37 is rotated in the opposite direction, that is when the clutch member 41 locks the gear 43 with the shaft 37, the shaft 37 will be given a greater rate of speed of rotation by reason of the proportion or ratio of the gears 16 and 43 with respect to each other and with respect to the gears 39—44.

Thus it will be seen that the shaft 37 will be given a slow degree of rotation in one direction and a quick degree of rotation in the opposite direction, for a purpose to be set forth.

The cam surface 55 and the gear 57 are rotated through the medium of the gear 58 on the shaft 59 and a gear 62 which is secured for rotation with the shaft 59 and gear 58, and this gear 62 meshes with another gear 63 secured to a shaft 64 for rotation therewith and which shaft is journaled in suitable bearings.

Another gear 65 is connected with the gear 63 for rotation therewith and this gear 65 meshes with a gear 66, the latter being secured to the shaft 23 for rotation therewith so that when the shaft 23 is rotated by the driving mechanism embodying the frictional drive elements 25—24 the gear 66 will be rotated, which in turn will rotate the gears 65, 63, 62, 58 and the gear 57 to operate the cam element 55.

These latter gears are so proportioned and the cam element or surface 55 is so located with respect to the gear 57 that it will engage

and shift the member 48 only at a predetermined time in the cycle of operation thereof.

- Loosely mounted upon the portion 38 of the shaft 37 is a sleeve 67 (see particularly Figures 4 and 7) and which sleeve is free to rotate upon and about the portion 38 of the shaft 37, the said portion 38 being at all times freely rotatable within the sleeve. Connected with the sleeve 67 is an arm 68, to the extremity of which is secured a threaded segment 69 and to the segment is connected a handle 70. The arm 68 is of such a length that the segment 69 will engage and rest upon the threaded shaft 11 so that when the shaft 11 is rotated the sleeve 67, arm 68 and segment 69 will be bodily advanced in directions lengthwise of the shafts 11 and 38. The handle 70 passes through a suitable aperture 71 in the top of the casing 72 so as to be readily accessible to the operator and the aperture 71 is elongated as shown in Figure 1, so as not to interfere with the advancing and retracting movement of the arm 68 and sleeve 67.
- 25 A rack member 73 is provided which passes through suitable apertures 74 in the casing and extends transversely of and across the shafts 11 and 38. The sleeve 67 is provided with an apertured portion 75 in which the rack 73 rests and is guided so that the teeth of the rack will engage the toothed portion 38 of the shaft 37 whereby when the shaft 37 is rotated the rack 73 will be advanced or retracted according to the direction of rotation of the shaft. Ears 76 may be provided adjacent the bifurcated portion of the sleeve so as to guide the rack. The segment 69 is also bifurcated as shown more clearly in Figure 5, and loosely mounted upon the shaft 11 is a sleeve 77 that is adapted to freely slide lengthwise of the shaft 11. This sleeve is also bifurcated as at 78 to receive and guide the rack 73, a portion 79 of the segment 69 projecting into the bifurcation (see particularly Figure 5) for holding the rack 73 in position. The bifurcation 78 of the sleeve 77 and the bifurcation of the segment 69 are so arranged that the arm 68 may be raised to elevate the segment 69 out of contact with the shaft 11 so as to permit free longitudinal movement of the sleeves 77 and 67 upon their respective shafts without disconnecting the rack 73 from the toothed portion 38 of the shaft 37.
- 50 Connected with the rack 73 is a pointer or indicator 80 which may be of any desired configuration adapted to move across the face of a surface 81 containing the subject matter 82 that is to be indicated.
- 55 By the provision of the toothed portion 38 of the shaft 37 the rack 73 and indicator will be given a movement from left to right or in the direction followed by anyone reading any text. When the indicator 80 reaches the end
- of the line or the limit of its movement toward the right, the shaft 11 will be automatically set in operation in the manner already set forth, that is by the engagement of the cam 55 with the member 48 to rock the lever 49 and shift the clutch member 13 to lock the gear 14 with the shaft 11. At the same time the shaft 37 will be locked for rotation through the medium of the same cam 55 shifting the member 48 and rocking the arm or lever 45 to shift the clutch member 41 and thereby unlock the gear 29 with respect to the shaft 37 and lock the clutch member 42 and gear 43 with respect to the shaft 37. This will cause the pointer or indicator 80 to be given a quick return movement and at the same time as the shaft 11 is being rotated, the segment 69, arm 68 and sleeve 67 will be advanced by the shaft 11 so that the pointer or indicator 80 will drop down to the next line at the extreme left thereof as indicated in dotted lines in Figure 2. The same operation will then be repeated, causing the pointer or indicator to successively move from left to right to the full end of one line and then drop down on its return movement to be properly positioned at the next line and so on.
- 55 Should it be desired to re-position the pointer or indicator 80 at any point on the text or matter being indicated thereby, it is only necessary to grasp the handle 70 and raise the segment 69 and arm 68 without interfering with the rack 73 and pointer 80, thereby disconnecting the arm 68 and segment 69 with respect to the shaft 11, which will permit these parts to be freely moved longitudinally of the respective shafts.
- 60 The entire operation of the mechanism may be controlled in any suitable manner such as by means of contact making and breaking devices 83 arranged within the circuit 84 which controls the motor (not shown) that drives the shaft 26.
- 65 If desired and in order to permit the rack 73 and pointer 80 to be folded with respect to the structure when not used, a suitable joint 85 (see Figure 1) may be provided therein.
- 70 While the preferred form of the invention has been herein shown and described, it is to be understood that various changes may be made in the details of construction and in the combination and arrangement of the several parts, within the scope of the claims, without departing from the spirit of this invention.

What is claimed as new is:—

1. A device of the character described embodying a pointer element, means for causing a continuous forward movement thereof in a predetermined path and for returning the element to its starting position, and means for causing the said element to be

bodily moved to position it for a forward movement in another path at the completion of movement thereof in the first recited path.

2. A device of the character described embodying a pointer element, means for causing a continuous forward movement therewith in a predetermined path and for returning the element to its starting position, and means for causing the said element to be bodily moved to position it for a forward movement in another path at the completion of movement thereof in the first recited path and as the pointer element is being returned to a position to commence its movement in the second recited path.

3. A device of the character described embodying a pointer element, means for causing a forward movement therewith in a predetermined path and for returning the element to its starting position, means for causing the said element to be bodily moved to position it for a forward movement in another path at the completion of movement thereof in the first recited path, and means for controlling the speed of advancing movement of said element.

4. A device of the character described embodying a pointer element, means for causing a continuous forward movement therewith in a predetermined path and for returning the element to its starting position, means for causing the said element to be bodily moved to position it for a forward movement in another path at the completion of movement thereof in the first recited path, and means for automatically reversing the direction of movement of the said element.

5. A device of the character described embodying a pointer element, means for causing a continuous forward movement therewith in a predetermined path and for returning the element to its starting position, means for causing the said element to be bodily moved to position it for a forward movement in another path at the completion of movement thereof in the first recited path, and means for disconnecting at will said element from its operating mechanism whereby the said element may be moved to any predetermined position with respect to its operating mechanism and independently thereof.

6. A device of the character described embodying a pointer element, means for causing a continuous forward movement therewith in a predetermined path and for returning the element to its starting position, and means for causing the said element to be bodily moved to position it for a forward movement in another path at the completion of movement thereof in the first recited path, the first said means embodying mechanism for moving the said element forwardly at one rate of speed and backwardly at a different rate of speed.

7. A device of the character described embodying a pointer element, means for causing a forward movement therewith in a predetermined path and for returning the element to its starting position, means for causing the said element to be bodily moved to position it for a forward movement in another path at the completion of movement thereof in the first recited path, the first said means embodying mechanism for moving the said element forwardly at one rate of speed and 70 backwardly at a different rate of speed, and means for controlling at will the rate of speed of said element in one direction. 75

8. A device of the character described embodying a pointer element, means for causing a continuous forward movement therewith in a predetermined path and for returning the element to its starting position, means for causing the said element to be bodily moved to position it for a forward movement 80 in another path at the completion of movement thereof in the first recited path, and means for starting and stopping the operation of the device at will.

9. A device of the character described embodying a pointer element, means for causing a continuous forward movement therewith in a predetermined path and for returning the element to its starting position, means for causing the said element to be bodily 90 moved to position it for a forward movement in another path at the completion of movement thereof in the first recited path, and means whereby said element may be folded with respect to its operating mechanism. 95

10. A device of the character described embodying a pointer element, means embodying a shaft for advancing and retracting said element, and means embodying a shaft for bodily shifting said element in a direction transverse to the direction of its advancing and retracting movement, each of said means embodying a shaft with which said element has operative connection, the connections between the element and one of said shafts adapting the element for free movement in directions lengthwise of the axis of rotation of the shaft. 110

11. A device of the character described embodying a pointer element, means embodying a shaft for advancing and retracting said element, and means embodying a shaft for bodily shifting said element in a direction transverse to the direction of its advancing 115 and retracting movement, each of said means embodying a shaft with which said element has operative connection, the connections between the element and one of said shafts adapting the element for free movement in 120 directions lengthwise of the axis of rotation of the shaft, the said element being adapted to be freely disconnected with respect to the 125

other of the said shafts to permit the element to be freely moved at will lengthwise of the first said shaft.

12. A device of the character described embodying a pointer element, means embodying a shaft for advancing and retracting said element, means embodying a shaft for bodily shifting said element in a direction transverse to the direction of its advancing and retracting movement, each of said means embodying a shaft with which said element has operative connection, the connections between the element and one of said shafts adapting the element for free movement in directions lengthwise of the axis of rotation of the shaft, means for actuating one of said shafts alternately forwardly and backwardly, and means for automatically controlling the direction of rotation of the last said shaft.

13. A device of the character described embodying a pointer element, means embodying a shaft for advancing and retracting said element, means embodying a shaft for bodily shifting said element in a direction transverse to the direction of its advancing and retracting movement, each of said means embodying a shaft with which said element has operative connection, the connections between the element and one of said shafts adapting the element for free movement in directions lengthwise of the axis of rotation of the shaft, means for rotating one of said shafts constantly in one direction, means for rendering the last said shaft active and inactive, means for rotating the other of said shafts forwardly and backwardly, and means for controlling the direction of rotation of the last said shaft.

14. A device of the character described embodying a pointer element, means embodying a shaft for advancing and retracting said element, means embodying a shaft for bodily shifting said element in a direction transverse to the direction of its advancing and retracting movement, each of said means embodying a shaft with which said element has operative connection, the connections between the element and one of said shafts adapting the element for free movement in directions lengthwise of the axis of rotation of the shaft, means for rotating one of said shafts constantly in one direction, means for automatically rendering the last said shaft active and inactive, means for rotating the other of said shafts forwardly and backwardly, and means for automatically controlling the direction of rotation of the last said shaft.

15. A device of the character described embodying a pointer element, means embodying a shaft for advancing and retracting said element, means embodying a shaft for bodily shifting said element in a direction transverse to the direction of its advancing and retracting movement, each of said means embodying a shaft with which said element has

operative connection, the connections between the element and one of said shafts adapting the element for free movement in directions lengthwise of the axis of rotation of the shaft, means for rotating one of said shafts constantly in one direction, means for rendering the last said shaft active and inactive, means for rotating the other of said shafts forwardly and backwardly at different rates of speed, and means for controlling the direction of rotation of the last said shaft.

16. A device of the character described embodying a pointer element, means embodying a shaft for advancing and retracting said element, means embodying a shaft for bodily shifting said element in a direction transverse to the direction of its advancing and retracting movement, each of said means embodying a shaft with which said element has operative connection, the connections between the element and one of said shafts adapting the element for free movement in directions lengthwise of the axis of rotation of the shaft, means for rotating one of said shafts constantly in one direction, means for rendering the last said shaft active and inactive, means for rotating the other of said shafts forwardly and backwardly, means for controlling the direction of rotation of the last said shaft, a common driving mechanism for said shafts, and means for varying at will the speed of operation of said driving mechanism.

17. A device of the character described embodying parallel elongated shafts, threads on one of the shafts, elongated substantially parallel teeth extending lengthwise of the other shaft, a sleeve loosely mounted upon the last said shaft and freely movable over said teeth in directions lengthwise of the shaft, an arm connected with said sleeve, a formation on said arm adapted to engage the threads on the other shaft whereby said arm and sleeve may be advanced longitudinally of the shafts, a pointer element movable with and with respect to the sleeve and arm, said formation being adapted to be disconnected from the threaded portion of said other shaft by rotating said sleeve about its respective shaft, and means for imparting rotation to said shafts.

18. A device of the character described embodying parallel elongated shafts, threads on one of the shafts, elongated substantially parallel teeth extending lengthwise of the other shaft, a sleeve loosely mounted upon the last said shaft and freely movable over said teeth in directions lengthwise of the shaft, an arm connected with said sleeve, a formation on said arm adapted to engage the threads on the other shaft whereby said arm and sleeve may be advanced longitudinally of the shafts, a pointer element movable with and with respect to the sleeve and arm, said formation being adapted to be disconnected

from the threaded portion of said other shaft by rotating said sleeve about its respective shaft, means for imparting a forward and backward rotation to said toothed shaft, 5 means for rotating the threaded shaft, and means for automatically controlling the operation of said shafts.

19. A device of the character described embodying a pair of shafts, a pointer element, 10 means for rotating the shaft forwardly and backwardly, means connecting said element with the last said shaft for forward and backward movement, means connecting said element with the other shaft for bodily movement in a direction transverse to the direction of movement of said element by the first said shaft, means for imparting a constant direction of rotation to said second shaft, and 15 means for interrupting the rotation of the second said shaft at predetermined times in the cycle of operation of the first said shaft and in either direction of rotation of the first recited shaft.

20. A device of the character described embodying a pair of shafts, a pointer element, 25 means for rotating the shaft forwardly at one rate of speed and backwardly at a different rate of speed, means connecting said element with the last said shaft for forward and backward movement, means connecting said element with the other shaft for bodily movement in a direction transverse to the direction of movement of said element by the first said shaft, means for imparting a constant direction of rotation to second said shaft, and 30 means for interrupting the rotation of the second said shaft at predetermined times in the cycle of operation of the first said shaft and in either direction of rotation of the first recited shaft. 40

In testimony whereof we have signed our names to this specification, on this 25th day of June, A. D. 1928.

ELIZABETH DAY.
MAURICE GOLDBERGER.
